TRANSFORMER

Application filed February 15, 1930. Serial No. 428,621.

Our invention relates to transformers and it has particular relation to means for obtaining any desired ratio of transformation.

In electrical translating devices, such as 5 transformers, having two windings disposed on an iron core, both being interlinked by the magnetic flux passing through the magnetic circuit formed by the iron core, the ampere turns in one winding would be equal to 10 the ampere turns in the other winding, and the ratio of secondary current to primary current would be inversely as the ratio of the number of turns in the windings were it not 15 for the exciting current of the transformer.

In practice, however, the ratio of secondary current to primary current varies from the theoretical or inverse turn ratio. This variation in the actual transformation ratio 20 from the theoretical value is inherent in all transformers and is caused by the exciting current that supplies the iron losses and sets up the magnetic flux in the transformer core.

The error in the transformation ratio may 25 be compensated for by adding one or more turns to the primary winding, or subtracting one or more turns from the secondary winding. Such compensation, however, may be only approximate since the addition or subtraction of a full turn may not give the exact 30 compensation required.

In transformers employed in connection 35 with measuring instruments, the variation of the actual ratio of transformation from the inverse turn ratio is of prime importance because it affects the accuracy of the measurement and, therefore, the transformer must be compensated accurately for this variation in transformation ratio.

In certain types of instrument transformers, for example, current transformers, errors in the ratio of transformation are compensated for by using fewer than the theoretically correct number of turns in the secondary winding. In transformers having a few turns in the secondary winding, it is difficult 45 to obtain the exact compensation required because the compensation necessary in most cases does not correspond to integral turns. Thus, if in a transformer having fifty secondary turns, a compensation of $1\frac{1}{2}\%$ is de-

sired, it is difficult to obtain this compensation as each turn represents 2% of the total winding and dropping one turn would provide too much compensation. In order to secure the exact compensation necessary a fractional turn ratio is required. 55

One object of our invention is to provide a transformer in which fractional turn ratios may be obtained.

Another object of our invention is to provide 60 a transformer in which the fractional turn ratios are obtained with a single conductor for each winding.

A still further object of our invention is to provide means for quickly and easily adjusting 65 the fractional turn ratio after the transformer has been assembled.

We have elected to illustrate our invention as applied to a current transformer, but it will be obvious that it is not limited to this 70 application.

Our invention may be best understood by reference to the following description and to the accompanying drawings, in which,

Figure 1 is a perspective view of a transformer 75 constructed in accordance with our invention.

Fig. 2 is a side elevational view, with parts removed, of the transformer illustrated in Fig. 1. 80

Fig. 3 is an end view of a transformer showing a modified form of our invention.

Referring to Figs. 1 and 2 of the drawings, our invention comprises, in general, a transformer core 2 and a plurality of windings 3 85 and 4 inductively related thereto.

The core 2 may be divided into a plurality of core sections, but is here illustrated as comprising two apertured core sections 5 and 6 having equal apertures but unequal lengths 90 and unequal cross sections of flux paths. The core sections 5 and 6 comprise a plurality of apertured laminations 7 having their apertures 8 in alignment, each section being separated from the next section by a non-magnetic 95 spacing member 9.

The windings 3 and 4 encompass all the sections of the core 2 and extend through the apertures 8. All the turns of winding 4 encompass all the core sections, while only some

of the turns of winding 3 encompass all the core sections.

As any turn that is closed around the core 2 through the apertures 8 constitutes a full turn of the winding, we provide the equivalent of a fractional turn winding by encircling the smaller core section 5 one or more times with the winding 3 without encircling the larger core section 6. Portions of the 10 spacer 9 are removed to permit turns of the windings 3 to encircle the smaller core 5, only.

When one turn encircles the smaller core section 5, the turns compensation is equal to

$$15 \quad \frac{A}{A+B}$$

where A and B are the lengths of the core sections 5 and 6, respectively. For example, if one-quarter turn compensation is required, the dimension A must be one-third of the dimension B with one turn encircling the smaller core section. To secure one-half turn compensation, two turns around the smaller core section 5 are necessary or one 25 turn around a core section twice as long as the core section 5.

We have found with this construction that fractional turn compensation may be attained to any desired degree, and that more 30 exact predetermination of the necessary compensation is possible.

It will be noted that the construction of the transformer is extremely simple and the number of turns linking the small core section 5 may be easily changed, which makes possible a change in the number of turns linking the smaller core member 5 after the transformer has been built and tested. The laminations 7 may be moved from one core 40 member to the other, thus varying the relative lengths of the core members. These adjustments are particularly advantageous on account of the difficulty in some cases of predetermining the exact compensation required.

45 Referring to Fig. 3 of the drawings, one core section 11 is disposed within the other core section 12. Most of the turns of winding 3 encompass both core sections 11 and 12 and relatively few turns of the winding 3 encompass one core section only, which may be either core section 11 or 12.

It will be evident from the above description that we have provided a transformer in which accurate fractional turn compensation 55 may be secured by using a single conductor for each winding, and one that is simple in construction and in which the required compensation may readily be effected.

Since many changes may be made in the 60 form and relation of the core members 5 and 6, and in the disposition of the winding 3 thereon without departing from the spirit and scope of our invention, we do not wish to be limited otherwise than as set forth in 65 the appended claims.

We claim as our invention:

1. A transformer comprising a plurality of core members each having uniform cross sections of flux paths and a winding disposed on the core members, a portion of said winding interlinking all core members and another portion of said winding interlinking less than all core members. 70

2. In an instrument transformer, a core comprising a plurality of core members each having a substantially constant cross-sectional area throughout the length of its magnetic path, primary and secondary windings interlinking all of said core members, at least one turn of one of said windings interlinking less than all the core members. 75

3. A transformer comprising two core members each having a substantially constant cross-sectional area throughout the length of its magnetic path, the cross section 85 of flux path of one member being a fractional part of that of the other member, a winding disposed on the core members, said winding having a plurality of turns thereof encircling the two core members and a relatively few 90 turns thereof encircling one of the core members. 90

4. A transformer comprising two apertured core members each comprising a plurality of laminations having equal apertures and equal cross sections of flux paths, said core members being separated by non-magnetic material and having their apertures in alignment, a winding disposed on aligned 100 legs of the core members and extending through the apertures, the majority of turns of said winding linking both core members and at least one turn linking only one core member. 100

5. In an instrument transformer, a core comprising two apertured core members formed from similarly shaped laminations, the cross section of flux path of one member being a fractional part of that of the other, the core members being separated by non-magnetic material and having their apertures in alignment, two windings of unequal 110 turns disposed on said core, the majority of turns of the winding having the greater number of turns linking both core members and extending through their apertures, at least one turn of the winding having the greater 115 number of turns linking only one core member. 115

6. An instrument transformer comprising 120 two core members each formed from a plurality of apertured laminations of the same shape and size and having their apertures in alignment, a winding interlinking said core members and extending through their apertures, the majority of the turns of said winding encircling both core members and at least one turn encircling only one core member. 125

7. An instrument transformer comprising 130 a core consisting of two apertured core mem-

bers having equal apertures and each having a constant cross sectional area throughout the length of its magnetic path, one core member having a smaller cross section of flux path than the other, a winding interlinking said core members and extending through their apertures, nearly all the turns of the winding encircling both core members and at least one turn encircling one core member only.

8. A current transformer, comprising a core structure consisting of a plurality of core members each comprising separate groups of magnetic laminations having unequal cross sections of flux paths, primary and secondary windings disposed on said core, the majority of turns of the secondary winding interlinking the plurality of core sections and relatively few turns of the secondary winding interlinking less than the plurality of core sections to produce fractional turn ratios between primary and secondary windings.

9. A current transformer, comprising a core structure consisting of two core members formed from two stacks of similar laminations, the stack comprising the flux path of one core member being much smaller than the stack comprising the flux path of the other core member, primary and secondary windings disposed on the core, most of the turns of the secondary winding interlinking both core members and at least one turn interlinking only the core member having the small flux path to produce fractional turn ratios between primary and secondary windings.

In testimony whereof, we have hereunto subscribed our names this 6th day of February, 1930.
